(57) **CLAIM**

The ornamental design for tripod legs and ladder for wildlife feeder, as shown and described.

DESCRIPTION

FIG. 1 is a perspective view of a set of tripod legs and a ladder for a wildlife feeder in accordance with the present invention;

FIG. 2 is a front elevation of the ladder flanked by the tripod legs;

FIG. 3 is a bottom view of the tripod legs and the ladder;

FIG. 4 is a top view of the tripod legs and the ladder;

FIG. 5 is a right side view of the tripod legs and the ladder as viewed in FIG. 2;

FIG. 6 is a rear elevation of the ladder flanked by the tripod legs; and,

FIG. 7 is a left side view of the tripod legs and the ladder as viewed in FIG. 2.

The barrel, timer feeder and lids shown in broken lines in FIGS. 1-7 denote the nature and environmental use of the design and are not part of the design.
